UNITED STATES PATENT OFFICE.

GEORGE A. HANLY, OF ELGIN, ILLINOIS.

PNEUMATIC VALVE MECHANISM.

1,152,811.

Specification of Letters Patent. Patented Sept. 7, 1915.

Application filed March 3, 1915. Serial No. 11,708.

To all whom it may concern:

Be it known that I, GEORGE A. HANLY, a citizen of the United States, residing in the city of Elgin, county of Kane, and State of Illinois, have invented certain new and useful Pneumatic Valve Mechanism, of which the following is a specification.

My invention relates broadly to means for controlling a liquid discharge through the utilization of an air body interposed between the liquid body and the discharge passage.

The present improvements over the device illustrated and described in my copending application Serial No. 874,178, filed November 27, 1914, to which reference is made, comprise a safety feature and a draining device. The object of the safety feature is to prevent the releasing of the sealing-air about the discharge orifice before there is a sufficient head of water in the tank to result in a complete discharge and the repocketing of a suitable quantity of air. The object of the draining feature is to provide means for emptying the tank more completely and, importantly, to provide means for withdrawing the water from the tank without inhibiting the intake of air beneath the sealing hood for the succeeding operation. Other objects and advantages will appear herein-after.

In the accompanying drawings, which form a part of this specification, I have illustrated substantially the device of my said copending application with the improvements hereinabove referred to thereon.

In these drawings Figure 1 is a vertical and substantially medial section longitudinally through a flushing tank equipped with my improvements, some of the parts being shown in full lines for convenience of illustration; Fig. 2 is a similar view, but with certain parts in another operative position; Fig. 3 is a transverse vertical section of the tank, as on the broken line 3-3 of Fig. 1, showing also, mainly in section, the trap and its connection to a closet bowl to be flushed; Fig. 4 is a perspective view of the air-pocketing hood-like element; Fig. 5 is a medial, vertical sectional view of the draining device similar to the views of the same element in Figs. 1 and 2, but on a larger scale; and Fig. 6 is a sectional view of the drainer, as on the line 6-6 of Fig. 5 in the direction of the arrows.

In my said copending application the parts hereinafter described as the drainer

and the safety catch 80 are not shown. In that application I have described how, when the water in the tank 10 is at a suitable height, as at the water line 16, Fig. 1, the further supply is cut off by the float 15 operating the valve 14 intermediate the supply pipe 12 and its discharge portion 13, and that when the float 15 is in the full line position of Fig. 2, the valve 14 is open providing a further flow of water to the tank. Also that when the rod 30, pivoted at 30^a, is moved by the handle 32 so that the catch 31 comes out of engagement with the cross piece 28^a of the frame 28 and the front end 25^a of the hood-like element 25 the hood-like element pivoted at 27 to an upward extension of the frame 28 will assume the dotted line positions of Fig. 1, discharging entrapped air from beneath the hood-like element 25 whereupon water in the tank is discharged through the opening 19 of the pipe-like element 18. Further, that when the hood-like element and frame 28 have again descended to their full line positions of Figs. 1 and 2 the flow of water through the discharge orifice 19 will continue until the hood-like element assumes the dotted line position of Fig. 2, the end A being drawn down with its lower edge just beneath the gradually falling water line until the air intake opening 40 is above the water line, at which time air will be admitted at the opening 40, and that as the end B of the hood-like device 25 becomes elevated substantially to the dotted line position of Fig. 2 the admitted air in the top thereof coming to the discharge opening 19 will break the siphonic action of the flow through the orifice 19 and that the discharge will thereupon cease; also that thereupon the hood-like element 25 will assume its normal position, as in Fig. 1, owing to the action of the counter-weight 43, with a body of air in the upper portion thereof and about the opening 19, sealing this opening against discharge when the water in the tank again rises above the same.

In this application I have added the draining device 70 to the structure of my said copending application, and have made a clearance for this element by elevating somewhat the upper wall 25^a of the hood-like element 25 over that shown in my said copending application. The draining device 70 comprises a cap or inverted cup preferably having a continuous side wall 71 and a top wall 72, a tube 73 being secured sub-

stantially centrally of the upper wall 72, and open from end to end. A plurality of spacers, suitably vanes, as 74, space the wall 71 from the pipe 18 when normally in position for use, extensions 74^a of the vanes being adapted to provide a clearance between the lower edge of the wall 71 and the bottom of the tank 10 so that water may flow around the lower edge of the wall 71 and into the orifice 19. The tube 73 preferably extends downward somewhat below the lower edge of the side wall 71, preferably the relative distance illustrated. It should not, however, extend below the normal gravity liquid line in the trap 17, or line *c-f* of Fig. 3 in the device illustrated. The drainer 70 may be slipped upon or withdrawn from the pipe-like element 18 at will, as for cleaning.

Assuming that water is at the normal liquid line 16 of Fig. 1 and the handle 32 is operated to release the frame 28 and hood-like device 25, air is discharged from beneath the latter and the liquid flow passes partly down through the pipe 73, but largely around the lower edge of the wall 71, upward inside the element 70, and then downward through the discharge orifice 19, and this flow continues until the water in the tank is discharged to the level of the bottom of the wall 71. Without the drainer in place, the hood 25 and the pipe or pipes 18, 17^a would constitute a siphon, and, as already mentioned, the discharge would be interrupted by air within the hood coming to the discharge orifice 19. Thereupon a considerable body of water still remaining in the hood 25 would fall back to the bottom of the tank, other water would be flowing into the tank through the supply pipe 13, and, inasmuch as the hood-like device 25 would assume its normal position shown in full lines in Figs. 1 and 2 as soon as the siphon is broken at the orifice 19, the intake orifice 40 naturally would descend closer to the water line in the bottom of the tank. I have found that where the pressure upon the pipe 12 is relatively great, or where conditions may require a rapid filling of the tank 10, the intake orifice 40 may become submerged before a sufficient supply of air has been admitted within the hood 25 to sustain a complete refilling of the tank. With the drainer 70 in position two siphons are formed, one by the hood 25 and the pipe 73, the other by the drainer walls 71, 72 and the pipe 18, 17^a. When air is discharged from beneath the hood 25 the flow through the pipe 18, 17^a is by gravity until the water in the tank falls below the level of the opening 75, when the siphon including the pipe 73 is put into action, and as the water in the tank falls the end A of the hood 25 descends and the intake opening 40 is supplying air to the interior of the hood

25. That part of the siphonic action which is due to the absence of air in the hood-like element 25 is broken when the air taken in at 40 comes to the opening 75 of the air pipe 73, and thereupon the hood-like element 25 immediately assumes its normal or substantially horizontal position. The discharge through the longer leg 17^a of the trap 17 is not discontinued, however, as the auxiliary siphon which includes the walls 71, 72 of the drainer 70 is now operating independently of the other siphon, and as the lower edge of the wall 71 is relatively close to the bottom of the tank, the flow passes through the orifice 19 and leg 17^a until the water in the tank has practically all been drained out, at which time the admission of air around the lower edge of the wall 71 breaks the siphonic action of the auxiliary device. From the drawings it will readily appear that during the action last mentioned the opening 40 will be maintained clear of the surface of the descending water for a considerable period, and the hood 25 is thus completely filled with air for a succeeding operation. With the drainer in position it is only necessary that the discharge through the orifice 19 be greater than the intake through the pipe 13 to insure a perfect discharge of the tank and a refilling of the hood 25 with air. When the siphon is broken with all the water but say a small layer in the bottom of the tank withdrawn, the water line in the trap 17 naturally falls to the line *c-f* of Fig. 3, and as the lower end of the open pipe 73 is above this line, air within the hood 25 is there effectively imprisoned, as well as in the upper portion of the leg 17^a. When the surface of the water in the tank 10 gradually rises and the air beneath the hood 25 is compressed and the water line beneath the hood gradually rises closer to the opening 19, air communication is had through the pipe 73 to the surface of the water in the trap 17 and the water line in the leg 17^a thereof is forced substantially to its position at 38, Fig. 3, the water in this leg being forced up the other leg 17^b and into the bowl 11, serving as a refill therefor. By the provision of a few small holes, as 76, near the lower edge of the wall 71 of the drainer 70 I avoid a rather objectionable gurgling noise due to the otherwise sudden breaking of the siphonic action.

The other feature of improvement mentioned is in the safety device 80 which comprises the bar 81 pivoted at 81^a and having a weighted catch element 82 adapted to engage the cross bar 28^b of the frame 28 as well as the end 25^c of the hood-like element 25, the same as does the catch 31, either thereof maintaining the hood 25 in air-imprisoning position. On the rod 15^a carrying the float 15 I provide a cross pin 83

adapted to engage the edge of a preferably two-piece or bifurcated extension 84 of the rod 81 so formed that when the rod 15^a is in its lowermost position, as in Fig. 2, the 5 weighted end 82 will be in its locking position, as in Fig. 2, and when the float 15 rises to a predetermined height, as in the dotted line position of Fig. 2, the pin 83 will engage the cam surface of the extension 10 84 and force the locking end 82 out of engagement with the cross piece 28^b and the end 25^a of the hood 25. I have found that unless there is a sufficient head of water in the tank before the flushing operation is be- 15 gun a true siphonic action through the pipe 18 will not be put into operation, and the hood 25 will not be drawn down into its locked position. The result is that the flow through the orifice 19 is continuous and at 20 the rate of intake through the pipe 13. It will be noted that when the safety catch 82 is in its holding position of Fig. 2 the operation of the other catch 31 will not release the hood 25 for a discharge and the handle 25 32 may be operated or trifled with at pleasure and no discharge will take place until a sufficient head of water is within the tank, at which time the catch 82 will be freed from its holding position, as illustrated in 30 Fig. 1. The working of the device as a whole is thus rendered safe from interference which would prevent its successful operation.

The drainer 70 is made of light sheet 35 metal and an ordinary metallic tube secured thereto with a tight joint, and the safety device is also preferably of light metallic construction. The air-pocketing hood 25, open only at the bottom portion of end A, 40 as at 26, and at the air intake, as 40, has its top wall 25^a preferably inclined upward from end portions, substantially as shown, to provide clearance for the drainer 70.

While I have illustrated and described a 45 preferred embodiment of these improvements it will be apparent to persons skilled in the art that changes and modifications may be made from the illustrative embodiments shown without departing from the 50 spirit of the invention.

All such changes and modifications are contemplated by me as fall within the scope of the appended claims.

The flushing device is applicable to various other uses than the one specifically shown, and in some uses an intermittent and automatic flushing operation will be found advantageous. In such cases the hand controlled latch 31 may be dispensed with and the intermittent flushing be made dependable upon the float controlled latch 80. Such intermittent discharge may also be made dependent upon the head of water in the tank, as, when such water rises above 65 the normal liquid line, as 16, or sufficiently

to cause the water beneath the hood 25 to rise to the orifice 19 the flushing discharge will automatically take place.

I claim:

1. The combination of a tank adapted to contain a liquid, a discharge element projecting upward in said tank and having a discharge orifice at the upper portion thereof, said discharge element having a trap normally below said discharge orifice, means 75 for imprisoning a quantity of air about said discharge orifice, and a siphon device in co-operative relation with said discharge element and orifice adapted to cause a liquid discharge through said orifice independently of said imprisoning means after a discharge through said orifice is started, said imprisoning means being adapted to prevent a discharge through said orifice until the imprisoned air about said orifice is released, and means for releasing air imprisoned by said imprisoning means. 80

2. The combination of a tank adapted to contain a liquid, a discharge element projecting upward in said tank and having a 90 discharge orifice at the upper portion thereof, said discharge element having a trap normally below said discharge orifice, a pivoted hood-like device adapted to imprison a quantity of air about said discharge 95 orifice, and an inverted cup-like siphon device about said discharge element and orifice adapted to cause a liquid discharge through said orifice independently of said hood-like device after a discharge through 100 said orifice is started, means for releasably holding said hood-like device in air imprisoning position, and means for supplying a liquid to said tank.

3. The combination of a tank adapted to contain a liquid, a discharge pipe having a portion thereof projecting upward in said tank and having a discharge orifice in said upwardly projecting portion, a pivoted hood-like device adapted to imprison a 105 quantity of air about said discharge orifice in said tank, means for releasably holding said hood-like device in air-imprisoning position, means for supplying a liquid to said tank, and a draining element comprising an 110 inverted cup-like siphon device about said discharge pipe in said tank and having its lower edge normally below said discharge orifice and so spaced from said pipe and orifice that a liquid in said tank may flow 115 around the lower edge of said draining element and into said discharge orifice. 120

4. The combination of a tank adapted to contain a liquid, a discharge pipe having a discharge orifice in said tank and a trap outside said tank and normally below said discharge orifice, means for imprisoning a body of air about said discharge orifice in said tank, a cup shaped device about said discharge orifice and constituting a siphon in 125 130

conjunction with said discharge pipe, said trap being adapted to contain a quantity of the liquid from said tank, means providing an air passage from above the normal liquid line in said trap to the space occupied by imprisoned air in said air imprisoning means, means for discharging air from said air imprisoning means whereby liquid in said tank may flow through said discharge orifice, the construction of said air imprisoning means being such as to provide an intake for air to said air imprisoning means to provide a body of air therein after a discharge of liquid through said discharge orifice.

5. The combination of a tank adapted to contain a liquid, an open end discharge pipe projecting upward in said tank, a pivoted hood-like device adapted to imprison a quantity of air about the open end of said discharge pipe in said tank, means for releasably holding said hood-like device in air imprisoning position, and a draining element comprising a hood-like device providing a siphon about said discharge pipe in said tank, said draining element having an air tube extending through a portion of said discharge pipe and open throughout its length, said air tube being in communication with the imprisoned air beneath said hood-like element when the device is normally in use, and a trap in said discharge pipe and adapted to contain a quantity of liquid normally below the open end of said discharge pipe, said air tube having its lower end normally above the normal liquid line in said trap.

6. The combination of a tank adapted to contain a liquid, a discharge pipe projecting upward in said tank and having a discharge orifice, a pivoted hood-like device about said pipe and orifice adapted to imprison a body of air about the same to provide a seal against water discharge therethrough, means for releasably holding said hood-like device in air imprisoning position, a siphon cap about said pipe and orifice having its lower edge below said orifice, said siphon cap being spaced from said pipe and orifice and from a wall of said tank whereby a liquid in the tank may flow through said siphon cap to said discharge orifice, said siphon cap having means providing an air vent open to imprisoned air beneath said hood-like element when the device is normally in use, said air vent means comprising an air pipe extending through a portion of said pipe, said pipe having a trap therein below said discharge orifice, said trap being adapted to contain a quantity of liquid, said air pipe opening into said discharge pipe at a point between the normal gravity liquid line in said trap and said discharge orifice.

7. The combination of a tank adapted to

contain a liquid, a discharge pipe projecting upward in said tank and having a discharge orifice therein, said pipe having a trap with a longer and a shorter leg below said discharge orifice, the longer leg of said trap being in direct communication with said discharge orifice, said trap being adapted to contain a quantity of liquid from said tank, a pivoted hood-like device in said tank adapted to imprison a body of air about said discharge orifice, means for releasably holding said hood-like element in air pocketing position when the liquid line in said tank is above said discharge orifice, and a draining cap about said pipe and orifice in said tank, said draining cap having walls spaced from said orifice and providing a passage-way for liquid from below said orifice to said orifice, the walls of said cap being formed to constitute a siphon in conjunction with said pipe and orifice when liquid is flowing through said orifice and pipe, and a vent pipe open throughout its length and in communication with imprisoned air beneath said hood-like device, said vent pipe extending substantially below said discharge orifice and to a point in said discharge pipe substantially above the normal gravity liquid line in said trap, and means for supplying a liquid to said tank.

8. The combination of a tank adapted to contain a quantity of liquid, a discharge pipe in said tank and having a discharge orifice therein, means for supplying a liquid to said tank, means for imprisoning a body of air about said discharge orifice and pipe in said tank, and means under the control of the rising water in said tank for releasing such imprisoned air to provide discharge through said orifice when the water in said tank rises to a predetermined height.

9. The combination of a tank adapted to contain a liquid, a discharge element having a discharge orifice in communication with the interior of said tank, a pivoted hood-like device adapted to imprison a body of air about said discharge orifice and to seal the same against liquid discharge therethrough, operable means for holding said hood-like device in air-imprisoning position, means for supplying a liquid to said tank, and means for automatically operating said holding means to release said hood-like device when the water in said tank rises to a predetermined height therein.

10. The combination of a tank adapted to contain a liquid, means for supplying a liquid to said tank, a discharge pipe having a discharge orifice projecting upward in said tank, a movable hood-like device adapted to imprison a body of air about said discharge orifice and to seal the same against liquid discharge therethrough when the liquid in said tank is above said discharge orifice, hand-controllable means for releasably

5 maintaining said hood-like device in air imprisoning position, and automatically releasable means for maintaining said hood-like device in an imprisoning position whereby said hand-controllable means may 10 be operated to release said hood-like device so as to discharge imprisoned air from beneath the same only when the automatic means are released, said automatic means 15 being under the control of the water in said tank when it reaches a predetermined height therein.

11. The combination of a tank adapted to contain a liquid, a discharge element in communication with the interior of said tank, a pivoted hood-like device about said discharge orifice adapted to imprison a body of air thereabout and to seal the same against liquid discharge when the liquid 15 line in said tank is above the same, means for releasably holding said hood-like device in air imprisoning position, said means being operable from outside said tank, a float 20 in said tank, and a holding and releasing device for maintaining said hood-like device in air-imprisoning position and operable by 25 said float to release said hood-like device when the water in said tank rises to a predetermined height therein.

12. The combination of a tank adapted to 30 contain a quantity of liquid, means for supplying a liquid to said tank, a float-and-valve device adapted to control the supply of liquid through said means, a discharge pipe projecting into said tank and having a 35 discharge orifice therein, said pipe having a trap adapted to contain a quantity of liquid, said trap being normally below said discharge orifice, means for imprisoning a body of air about said discharge orifice in 40 said tank so as to seal the same against liquid discharge therethrough when the liquid in said tank is above said discharge orifice, means operable from without said tank for discharging imprisoned air from said air-imprisoning means whereby a liquid may 45 flow through said discharge orifice, and means under the control of said float for controlling the discharge of such imprisoned air whereby such imprisoned air may 50 be discharged by said discharging means only when the water in said tank reaches a predetermined height therein.
